(57) CLAIM

The ornamental design for an electronic device with pair of display screens or portions thereof each with animated graphical user interface, as shown and described.

DESCRIPTION

The file of this patent contains at least one drawing/photograph executed in color. Copies of this patent with color

drawing(s)/photograph(s) will be provided by the Office upon request and payment of the necessary fee.

FIG. 1 is a first image of an electronic device with pair of display screens or portions thereof each with animated graphical user interface showing our new design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The peripheral dashed broken lines illustrate a display screen portion thereof, and form no part of the claimed design.

The appearance of the graphical user interface transitions between the images shown in FIGS. 1-6. The process or period in which one image transitions to another forms no part of the claimed design.
